LIFE GUARD CHAIR STAND

Richard O. Lightfoot, West Los Angeles, and Alfred Z. Konopka, San Fernando, Calif., assignors to Paddock of California, Van Nuys, Calif., a corporation of California

Application October 30, 1959, Serial No. 58,131

Term of patent 14 years

(Cl. D34—5)

FIG. 1.

FIG. 2.

FIG. 3.

FIG. 4.

Fig. 1 is a front perspective view of our new design;
Fig. 2 is a side elevation view thereof;
Fig. 3 is a back elevation view thereof; and
Fig. 4 is a plan view taken from the top thereof.
The dominant features of our design are shown in full lines.

We claim:

The ornamental design for a life guard chair stand, as shown and described.
